(57) **ABSTRACT**

An accessory for a firearm includes a deflector structured to alter a path of discharge gasses and/or debris after such gasses and debris pass a Loaded Chamber Indicator (LCI) of the firearm. The LCI indicates a presence of a cartridge within a firing chamber of the firearm, but openings within and around the LCI also provide a path for hot gasses and debris to strike accessories, which causes fouling and other deterioration.

FIREARM GAS DISCHARGE DEFLECTOR**CROSS-REFERENCE TO RELATED APPLICATIONS**

This application is a non-provisional of and claims benefit to U.S. provisional patent application No. 63/069,505, filed Aug. 24, 2020, titled FIREARM GAS DISCHARGE DEFLECTOR, the disclosure of which is incorporated herein by reference in its entirety.

TECHNICAL FIELD

This disclosure relates to firearm accessories, and, more particularly, to a deflector for preventing discharge gasses and debris from contaminating portions of the firearm or firearm accessories.

BACKGROUND

Many firearms, especially pistols, include a Loaded Chamber Indicator (LCI) to indicate that a bullet, or round, is in the firing chamber. Most firing chambers completely surround a loaded round, and, without an LCI, it is very difficult or impossible for a shooter to know whether the chamber is loaded, since the round is completely covered and cannot be seen. Without an LCI, there is no external distinction between an empty chamber and one that is loaded.

Firearms with an LCI instead provide an indication, such as a colored tab, that raises to enter the shooter's field of view to indicate that the chamber is loaded. Typically an LCI includes a small metal bar with a red tip. When no round is chambered, the LCI is not activated and no red tip is visible. Conversely, when a round is chambered, the metal bar is physically moved upward so that the red tip extends away from the chamber and into the shooter's view. In this way the shooter can readily determine whether the chamber is loaded by inspecting for the presence of the red tip. If the red tip of the LCI is visible, the chamber is loaded; if no such tip is visible, the chamber is empty. Not all LCIs are physically formed in the same way but they all function in the same way—that is, they all provide an indication of a loaded chamber.

Due to the physical structure of the LCI, the top of the chamber is generally not sealed. This means that, when the firearm is fired, hot gasses and debris from the exploding gunpowder rushes out of the chamber in any available direction. Since the LCI is generally mounted at the top of the chamber, to provide the best visibility, this means that significant gas and debris rushes out from the top of the gun. These gasses and debris can not only foul equipment, but also can be ejected onto surfaces, such as glass and plastic sights. Over time the debris can accumulate to cause the sight surface to become cloudy, and the ejected gasses may even damage the surface over time.

Many government entities are requiring all new weapons to include an LCI, and thus the problem is getting more significant.

Embodiments of the disclosure describe a new type of accessory control.

BRIEF DESCRIPTION OF THE DRAWINGS

FIG. 1 is a side perspective view of a conventional pistol having a Loaded Chamber Indicator (LCI) including a sighting accessory.

FIG. 2 is a front perspective view illustrating how ejection gasses and debris accumulate on the sighting accessory illustrated in FIG. 1.

FIG. 3 is a side perspective view of a pistol having an LCI and including a gas discharge deflector, according to embodiments of the invention.

FIG. 4 is a magnified perspective view of the pistol of FIG. 3 illustrating a modified gas discharge path due to the presence of the gas discharge deflector, according to embodiments of the invention.

FIGS. 5A and 5B are cross-sectional views that illustrate how the gas discharge deflector of FIG. 3 may be inserted into and retained by elements of the sighting accessory.

DETAILED DESCRIPTION

Embodiments of the invention employ a gas discharge deflector to divert hot ejection gasses and debris from hitting a desired portion of the firearm, such as a sighting lens. Such hot ejection gasses and debris are generated when the firearm is discharged as a result of the rapidly burning gunpowder from a cartridge fired by the firearm. Embodiments are also directed to an accessory for a firearm that includes a deflector structured to alter a path of discharge gasses and/or debris after such gasses and debris pass a Loaded Chamber Indicator (LCI) of the firearm. The LCI indicates a presence of a cartridge within a firing chamber of the firearm, but openings within and around the LCI also provide a path for hot gasses and debris to strike accessories, which causes fouling and other deterioration, as described in detail below.

FIG. 1 illustrates the typical position of a Loaded Chamber Indicator (LCI) 20 at the top of a firearm, in this case a pistol 10, as well as a sighting accessory 14. In FIG. 1, the sighting accessory 14 is a target sight commonly called a red dot sight. Such sights generally include a transparent surface, which is also called a sight glass 16, near the LCI 12, as is illustrated in FIG. 1. Embodiments of the invention are applicable to any type of accessory where it is desired to shield the accessory or portions of the firearm itself from ejection gasses and/or debris expelled from a firing chamber of the firearm when the firearm is discharged.

FIG. 2 illustrates an example portion 20 of the sight glass 16 affected by the ejecting gas and debris from the cartridge 45 when the weapon is fired. When the gun is fired, the hot gasses and debris from the burning gunpowder of the cartridge rush out of the firing chamber, past the openings made by the LCI 12, toward the top of the pistol 10 and accessory 14. Significant gas and debris may be ejected toward the transparent sight glass 16 of the target sight 14. The exhaust from the explosion projects onto the lens 16 of the sight 14. The particles 20 from the exhaust also collect onto the lens 16 over time. The collection of particles 20 quickly accumulates, and, if enough debris accumulates on 50 the target sight, renders the sight useless by blocking the view of the user. The gasses themselves may also affect the material of the lens of the sight glass 16, or coatings used in or on the sight glass. The particles 20 illustrated in FIG. 2 are only one example of how such particles may be distributed on a sight glass 16. In reality, the particles 20 may have different patterns, shapes, densities, etc.

FIG. 3 is a side perspective view of a pistol 110 having an LCI 112 and a targeting sight accessory 114 with a transparent lens or surface 116. Further illustrated in FIG. 2 is a gas discharge deflector 120, which functions to route hot gasses away from the targeting sight 114 when the weapon is being fired.

The deflector 120 may be formed of any suitable material, such as plastic or metal. In one embodiment the deflector 120 is composed of glass-filled nylon, but may be formed of any material that is durable and may be formed or placed to block cartridge gasses and/or debris. When installed onto a pistol 110, the deflector 120 may be located between the LCI 112 and any accessory that is desired to be shielded from the discharge gasses. Or, the deflector 120 may block the discharge gasses and particles from a portion of the firearm 110 itself. In the installation illustrated in FIG. 3, the deflector 120 is inserted into a recess or pocket of the targeting sight 114, and is retained by a crossbar 122, as described in detail with reference to FIGS. 5A and 5B. Other retention mechanism may operate to maintain the deflector 120 in position. The position of the deflector 120 is such that it blocks some, most, or all of the exhausted gasses that vent around the LCI 112, so the gasses are blocked from reaching or affecting the sight glass 116 or other portion of the accessory 114 or firearm 110. This reduces or eliminates the accumulation of debris from depositing onto the sight glass 116 or elsewhere. The deflector 120 also prevents or substantially reduces gasses from reaching the surface of the sight glass 116, to prevent damage from the gas. Note, too, that the deflector 120 may be shaped and placed in such a way to not interfere with the operation or the function of the LCI 112, thus allowing the LCI 112 to continue to function as a safety feature of the pistol 110.

In the illustrated embodiment of FIG. 3, the deflector 120 includes a scallop or indented shape 121 to help route the exhausted gasses away from the surface of the sight glass 116. Other embodiments may have different shapes, of either the deflector 120 itself or any indentations 121, but act to provide the same or similar function of preventing at least some of the gasses and debris from the exploding cartridge from reaching or accumulating on the surface of the sight glass 116, or other portion of the firearm 110 or firearm accessory 114 desired to be shielded.

FIG. 4 is a magnified perspective view of the pistol of FIG. 3 illustrating a modified gas discharge path 130 due to the presence of the gas discharge deflector 120, according to embodiments of the invention. In this embodiment the LCI 112 is in the active position, which indicates that a cartridge is loaded into the firing chamber of the piston 110. The indication may be seen by a shooter through or around the accessory 114, or the shooter may use his or her finger to determine whether the LCI 112 is in the active position, which indicates that a cartridge is present, or the inactive position, which indicates that the firing chamber is empty.

An example path 130 of the discharging gas and debris due to discharging the firearm is illustrated in FIG. 4. Initially these discharged gasses are directed upward from the chamber, around and through the LCI 112 toward the top of the firearm 110. In firearms that have the gas discharge deflector 120 installed, the gasses and debris strike the deflector 120 before reaching the forward lens 116 of the accessory 114. The discharge deflector 120 creates a physical barrier preventing the gas and debris from reaching the lens 116, and instead causes the discharge gasses and debris to be routed away from the firearm 110, lens 116, or other accessory or portion of an accessory desired to be so protected from the gas discharge. FIG. 4 illustrates how the discharge deflector 120 blocks or interrupts the discharge path 130 of the blocked gasses so that they are diverted away from the firearm 110 and accessory 114. In practice, the discharge gasses may not flow exactly as depicted in FIG. 4, but in any case are generally directed away from the lens 116 and the accessory 114.

In some embodiments, the gas discharge deflector 120 is removable from the accessory 114, while in other cases the gas discharge deflector 120 may be integrated into the accessory itself. In yet other embodiments the gas discharge deflector 120 may be integrated into the firearm, such as a part of the LCI 112 itself.

FIGS. 5A and 5B are cross-sectional views that illustrate how the gas discharge deflector 120 may be inserted into and retained by elements of the sighting accessory 114. With reference to FIG. 5A, the gas deflector 120 is shaped with a groove 123 or indentation. The groove 123 of the gas deflector 120 is shaped to be mechanically retained by the crossbar 122 of the sighting accessory 114. The sighting accessory 114 also includes a pocket or recess 140 shaped to generally accommodate the shape of the gas deflector 120. In general, to insert the gas deflector 120 into the sighting accessory 114, a user inserts the gas deflector in the direction of the indicated arrows toward the recess 140 of the sighting accessory, where a lip of the groove 123 contacts the crossbar 122. In one embodiment, further pressure of the gas deflector 120 toward the recess 140 causes the lip of the groove 123 to deform or deflect under the rigid crossbar 122, until finally snapping into place, as illustrated in FIG. 5B. In other embodiments the recess 140 is sized to be slightly larger than the gas deflector 120, and the gas deflector is forced downward while being pressed into the recess 140. In other embodiments a combination of both of these movements occur, where the lip of the groove 123 may yield somewhat while the gas deflector 120 itself may deflect somewhat, until the groove 123 is positioned against the crossbar 122 as illustrated in FIG. 5B. The gas deflector 120 may be removed by reversing the process, by pulling the gas deflector in the direction opposite the arrows illustrated in FIG. 5A.

In other embodiments, the gas deflector 120 may be wholly integrated into the accessory 114. In such an embodiment the accessory 114 may include a gas deflector portion that is formed coextensive with the accessory. In such an embodiment the crossbar 122 may be inserted into a receiving hole of the accessory 114 to retain the accessory itself in place.

In yet other embodiments the gas deflector 120 may be formed as a separate piece from the accessory 114, but the gas deflector 120 is permanently fixed into the accessory during or after manufacture. In such an embodiment the gas deflector 120 may be held in place in the position illustrated in FIG. 5B by, for example, glue or cement, as well as mechanical fasteners such as screws or pins. In this way the gas deflector 120 may be manufactured as a part separately from the accessory 114, but permanently retained within the accessory.

The previously described embodiments of the disclosed subject matter have many advantages that were either described or would be apparent to a person of ordinary skill. Even so, all of these advantages or features are not required in all versions of the disclosed apparatus, systems, or methods.

Additionally, this written description makes reference to particular features. It is to be understood that the disclosure in this specification includes all possible combinations of those particular features. For example, where a particular feature is disclosed in the context of a particular aspect or embodiment, that feature can also be used, to the extent possible, in the context of other aspects and embodiments.

Also, when reference is made in this application to a method or process having two or more defined steps or

operations, the defined steps or operations can be carried out in any order or simultaneously, unless the context excludes those possibilities.

Furthermore, the term "comprises," "includes," and their grammatical equivalents are used in this application to mean that other components, features, steps, processes, operations, etc. are optionally present. For example, an article "comprising" or "which comprises" components A, B, and C can contain only components A, B, and C, or it can contain components A, B, and C along with one or more other components. Similarly, an article "including" or "which includes" components A, B, and C can contain only components A, B, and C, or it can contain components A, B, and C along with one or more other components.

Also, directional words such as "right," "left," "up," "down," "forward," or "backward" are used for convenience and in reference to the views provided in figures.

Although specific aspects of the disclosure have been illustrated and described for purposes of illustration, it will be understood that various modifications may be made without departing from the spirit and scope of the disclosure. Accordingly, the invention should not be limited by the particular embodiments presented herein.

I claim:

1. A firearm, comprising:
a Loaded Chamber Indicator (LCI) that indicates when a cartridge is loaded into a firing chamber of the firearm;
and
a deflector structured to alter a path of discharge gasses after the discharge gasses pass the LCI.
2. The firearm of claim 1, in which:
the deflector is part of an accessory; and
the deflector is structured to block a gas path between the LCI and the accessory.
3. The firearm of claim 2, in which the accessory is a sight, and in which the deflector is structured to block a gas path between the LCI and a lens of the sight.
4. The firearm of claim 2, in which the deflector is a removable part of the accessory.
5. The firearm of claim 2, in which the deflector is a fixed part of the accessory.

6. The firearm of claim 2, in which the deflector is separate from but permanently attached to the accessory.

7. The firearm of claim 2, in which the deflector is further structured to block debris from striking the accessory.

8. The firearm of claim 1, in which the deflector does not interfere with an operation of the LCI.

9. The firearm of claim 1, in which the deflector includes a scalloped shape structured to alter the path of discharge gasses.

10. The firearm of claim 1, in which the deflector is formed from glass-filled nylon.

11. An accessory for a firearm that includes a Loaded Chamber Indicator (LCI) for indicating a presence of a cartridge within a firing chamber of the firearm, the accessory comprising:

a deflector structured to alter a path of discharge gasses after the discharge gasses pass the LCI.

12. The accessory of claim 11, in which:
the deflector is a component of the accessory; and
the deflector is structured to block a gas path between the LCI and the accessory.

13. The accessory of claim 12, in which the accessory is a sight, and in which the deflector blocks a gas path between the LCI and a lens of the sight.

14. The accessory of claim 12, in which the deflector is a removable part of the accessory.

15. The accessory of claim 12, in which the deflector is a fixed part of the accessory.

16. The accessory of claim 12, in which the deflector is separate from but permanently attached to the accessory.

17. The accessory of claim 12, in which the deflector is further structured to block debris from striking the accessory.

18. The accessory of claim 11, in which the deflector does not interfere with an operation of the LCI.

19. The accessory of claim 11, in which the deflector includes a scalloped shape structured to alter the path of discharge gasses.

20. The accessory of claim 11, in which the deflector is formed from glass-filled nylon.
